UNITED STATES PATENT OFFICE.

ROBERT L. WILLIAMS, OF NEWTON, MASSACHUSETTS, ASSIGNOR TO SUBMARINE SIGNAL COMPANY, OF WATERVILLE, MAINE, A CORPORATION OF MAINE.

BELL-BUOY.

1,164,772.

Specification of Letters Patent. Patented Dec. 21, 1915.

Application filed November 29, 1909. Serial No. 530,292.

To all whom it may concern:

Be it known that I, ROBERT L. WILLIAMS, of Newton, in the county of Middlesex and State of Massachusetts, a citizen of the 5 United States, have invented a new and useful Improvement in Bell-Buoys, of which the following is a specification.

The problem in bell buoys, especially those used in submarine signaling, is to secure a 10 signaling mechanism which shall be durable and compact and shall always have the same carrying power, so that when the signal is first heard on board ship a fair estimate may be made of the distance of the ship 15 from the signal. Such signals are caused automatically by wave motion which, acting on the floating buoy, raises and lowers it, a striking mechanism of constant power being operated by a sea anchor or other part 20 which is connected with the buoy in the still water at some depth below the surface, but is movable with relation to the buoy and is detained by its hold on the water as the buoy moves in either direction.

25 The present invention relates to improvements in bell buoys of this class and it is embodied in a mechanism shown in the drawings so constructed that the bell clapper is operated by the releasing of a compressed spring, so that the clapper will always be operated by a blow of given 30 strength.

The invention will be understood by reference to the drawings, in which—

35 Figure 1 is an elevation partly in section of a buoy embodying my invention. Fig. 2 is a vertical section of the bell and bell operating mechanism taken on line 2—2 of Fig. 3. Fig. 3 is a vertical section taken 40 on a plane at right angles to Fig. 2, and Fig. 3^a is a section on an enlarged scale showing one of the stuffing boxes on the main shaft. Fig. 4 is a horizontal section taken on line 4—4 of Fig. 2.

45 A is the float which may be of ordinary construction and is mounted upon a tube A¹ to the lower end of which is attached the bell operating mechanism and bell B. C is the case containing the operating mechanism. To its lower end is attached the bail A² by which the anchor chain A³ is attached to the buoy. The lower end of the tube A¹ is reinforced by the cap A⁴ which sets into it and is riveted thereto, the cap 50 being provided with a flange A⁵ which is

bolted to the flange C¹ surrounding the upper edge of the case C. The case containing the operating mechanism is intended to be filled with oil or other lubricant and for that reason is so put together that there 60 shall be no leakage. Openings closed by screw plugs c² are provided through which it may be filled. The case C is closed at its upper end as at C² and at its lower end is closed by the plate C³ bolted thereto. This 65 plate C³ contains a central opening through which the operating mechanism is connected to the clapper as will be below described. Dowel pins c assist in assembling the plate 70 and case.

B¹ is the clapper, the rod b of which passes up into a recess in the plate C³ and is keyed and pinned to a rock shaft B² to turn therewith. The rock shaft is mounted in bearings located one on each side of the 75 clapper rod. The lower half c¹ of each bearing forms part of the upper side of the plate C³. A cap-shaped yoke piece c² forms the top of the bearings and is bolted to the plate C³. These parts are provided with a 80 suitable packing to prevent leakage.

As shown the packing comprises rubber washers b³ mounted on the rock shaft B² to rotate therewith one on each side of the clapper rod and engaging the bearings. 85 Elastic gaskets b⁴ also of rubber lie between the washers b³ and the sides of the upper end of the clapper rod which is recessed for the purpose. This construction is very desirable because the bearings are thus 90 protected from corrosion and the interior of the case from leakage. A rubber gasket C¹¹ set into a groove in the upper surface of the plate C³ packs the joint between the plate C³ and the lower end of the case C. To each 95 end of the rock shaft B² is also attached a rocker arm B³, the plate C³ being recessed for the purpose. One of these rocker arms is shown in Fig. 3 and both are shown in 100 Fig. 2. Together they form a yoke-like piece. These rocker arms are within the case and are connected by a pin d which passes through a crosshead d¹ attached to a rod D, the upper end of which sets into a socket piece D¹ in which it has slight play. The socket piece is carried by a crank pin E supported between two ratchets F, G, operated by the pawls f, g. To the yoke piece 105 c² is attached an annular plate H to receive the lower end of the spring J, this plate 110

being also supported on uprights c^3 cast on the plate C^3 . The upper end of the spring is confined in a four-arm spider H^1 which is screwed onto a threaded section of the rod 6 D so that the spring is held under some compression. The spring tends in expanding to throw the clapper B^1 against the bell B . Between the lower end of the socket D^1 and the spider H^1 are a number of washers d^2 10 so as to adjust the motion of the rod D and socket D^1 , with relation to each other. There should be a certain amount of play between the two however as will be below described. Perforations d^3 are provided to allow for 15 the draining of the chamber between the socket and the end of the rod when the rod closes in to the socket.

From the description so far given it will be seen that the turning of the ratchets F, G, 20 will, through the action of the crank pin E in moving from its uppermost to its lowest position, depress the rod D so as to throw the clapper away from the bow of the bell and at the same time compress the spring. 25 After the crank pin has passed its lower dead center the spring in expanding will cause the clapper as shown in Fig. 3 to strike the bell with a blow of uniform strength due to the force of the spring, the clapper being free to rebound after the blow owing to the yielding character of the connection between the rod D and socket D^1 . The expansion of the spring will drive the 30 crank pin and the ratchets F, G, forward, the crank pin being perhaps thrown by momentum beyond its upper dead center so as to begin anew the compression of the spring. The ratchets will be immediately engaged by the pawls and the further compression 35 of the spring will begin at once. This is possible because there is no connection between the socket D^1 and the rod D. The upper end of the rod lies in the socket and as the spring expands as it will after the 40 crank pin has passed its lower dead center it will give a quick throw to the socket-piece and crank pin and as there is no connection between the socket and the rod the crank pin will be free to turn as far as its 45 momentum will carry it.

The pawls f , g , are four in number. Two are mounted on the plate F^1 and two on the plate G^1 . The ratchet F has a shaft f^1 which turns in a bushing f^2 . The pawl plate F^1 also turns on this bushing f^2 and is pinned to a pinion F^2 also on the bushing f^2 and in mesh with a gear F^3 on shaft M. The plate F^1 and pinion F^2 are free to turn 55 on the bushing. The bushing f^2 in which is the shaft f^1 is forced into a hub F^4 in the support N attached to plate C^3 by bolts c^4 . In like manner the ratchet G has a shaft g^1 turning in the bushing g^2 . The pawl plate G^1 free to turn thereon is pinned to the 60 pinion G^2 which is somewhat smaller than 65

the pinion F^2 and is in mesh with an idler pinion g^3 on a stud mounted in the hub g^4 on the support N¹ fastened to the plate C^3 . This idler g^3 is in mesh with the gear G^3 on the shaft M. The bushing g^2 is forced 70 into a hub G^4 on the support N¹ also bolted by bolts c^4 to the plate C^3 .

By inserting the idler g^3 between the gears G^2 and G^3 it will be noted that the movement of the shaft M with its gears F^3 75 and G^3 in a given direction will cause the pawl plates F^1 , G^1 to rotate in opposite directions so that one of the pairs of pawls will act to drive its ratchet while the other pair of pawls is riding over its ratchet's 80 teeth to a position where it will engage them and drive the ratchet when the shaft M changes its direction of rotation.

The bearings M¹ for the shaft M project from the opposite sides of the case C and 85 to prevent leakage stuffing boxes M² of peculiar construction are provided through which the shaft M projects. As shown these stuffing boxes are constructed as follows.

Each bearing M¹ is recessed at its end as 90 at m to receive a ball bearing which comprises an inner raceway m^1 on the shaft M to receive the balls, and another raceway m^2 which sets into the recess and is held therein against a suitable shoulder by an annular 95 plug m^3 which is pinned to the bearing by pins m^4 . Against the plug m^3 sets a hard rubber washer m^5 . The contacting surfaces of these two parts are smooth so that the washer m^5 may move easily with relation to 100 the plug m^3 . Against the washer m^5 is a soft rubber gasket or ring m^6 which is compressed between the washer m^5 and a washer m^7 of soft rubber. A pin m^8 connects the hard rubber washer m^5 with a lipped plate 105 m^8 passing through the soft rubber washer m^7 in so doing. The diameter of the opening in the plate m^8 is somewhat larger than that of the shaft M and is threaded on its interior to receive the ring m^{10} which screws 110 into it and is pinned to the shaft M. The plate m^8 has a number of sockets m^{11} in its face and the ring m^{10} has a lug carrying a screw m^{12} to fit whichever of these openings it can register with when this part of the 115 apparatus is assembled. In setting up this packing, the ring m^{10} being fixed to the shaft M, pressure is secured by turning the plate m^8 which advances to compress the various members and is locked by bringing 120 one of the sockets m^{11} into registry with the screw m^{12} which is then screwed into it. The hole in the washer m^5 for the pin m^8 is sufficiently deep to allow this adjustment without crowding the end of the pin m^8 .

Motive power is provided for the operation of the striker by counterbalanced vanes. For this purpose the shaft carries at each end a sleeve P which is preferably keyed thereto by a key p as well as fastened by a 130

5 bolt p^1 . Each sleeve has two sets q , r , of arms projecting therefrom, one set q having attached to them the vanes Q which may be of any desired shape and the other set carrying counter-balances R of sufficient weight to hold the vanes normally in horizontal position. Braces q^1 are provided for the vanes Q and a cross brace q^2 may also be provided for strength. An important feature of this construction is that the shaft M is free to rotate to any required extent. In buoys heretofore constructed the moving element by which power is applied to operate the clapper mechanism has had only a very limited movement. Such construction has proved faulty in those cases where the buoy is subject to very heavy seas so that the moving parts strike such stops or parts which limit their movement with great violence. 10 Such action soon breaks or wears the mechanism so that it becomes useless. Such buoys therefore require constant watching and repair. In the buoy shown, the vanes may rise into the plane of the axis of the 15 buoy or even in extreme cases may pass through a complete circle without in any way disarranging the striking mechanism. On the contrary during all this movement the vanes will be performing their ordinary 20 function. This is due not only to the absence of stops but to the use of a gear connection between the shaft and the operating mechanism. The counter-weights serve to 25 bring the vanes back to a normal operative 30 position as opportunity offers.

35 The bell B is preferably attached to the bottom plate C^3 of the case by means of 40 holders S which are semicircular in shape and are held to the bottom of the case by screws s . The upper part of the bell is provided with a projecting flange s^1 which lies in the groove formed by the lip s^2 of the holder. A rubber washer s^4 lies between the 45 top of the bell flange and the bottom of the plate C^3 . A rubber ring s^{14} encircles the edge of the flange s^1 and a rubber washer s^3 lies between the bell flange and the holder lip s^2 . These rubber packings serve to provide an elastic or yielding mounting for the 50 bell so that its vibration will not be deadened and also so that it will yield slightly when struck by the clapper so that the clapper will not tend to crack it.

55 The clapper rod b has a peripheral groove b^1 and the clapper proper is attached thereto by a pin b^2 which passes through a hole in the clapper and engages the rod at the groove. The bell is thus rotatable with relation to the case so that if its bow becomes 60 worn the bell may be turned slightly to offer a new surface to the clapper. In the same way the clapper is rotatable with relation to its rod so that as one face of the clapper becomes worn it may be turned slightly 65 to offer a new striking face with which to

strike the bell. These features are desirable in view of the wear which both bell and clapper receive.

70 The bell mechanism is operated by wave motion. The buoy A rises and falls with the motion of the waves while the vanes Q because of their position and area serve as a drag and as the buoy rises hold back assuming an angular position with relation to the axis of the buoy, thus causing the shaft M to turn. As the buoy falls again the vanes assisted by the counterweights R tend to resume their horizontal position and if the movement of the buoy is sufficiently great they may pass their horizontal position so as 75 to point upward, perhaps even passing a vertical position, turning the shaft M in an opposite direction. In a heavy sea however these motions may be exaggerated so that the shaft may be given a complete revolution, 80 though of course this is not necessary to the practical operation of the mechanism, nor is it usual in practice.

85 Each movement of the shaft M causes an advancing movement to be given to one of 90 the pairs of pawls, f , g , and consequently to the ratchets F , G , and the crank pin E when the crank pin is passing from its upper to its lower dead center; the spring J being compressed during this time and the 95 clapper being forced into striking position. When the lower dead center is passed the spring not only lifts the rod D thus causing the clapper to strike the bell, but gives the ratchets an impetus which, as they are free 100 to turn as far as they will go on account of the sliding connection between the socket piece and the end of the rod D , lifts the crank pin and carries it by momentum perhaps over its dead center, when the pawls immediately catch the ratchet teeth and the wave motion immediately becomes effective 105 again to cause the operation of the clapper.

110 It will thus be seen that the value of this apparatus depends largely upon the fact that its vanes are free to move in either direction as far as the particular impulse given by the waves to the float may require without danger of breakage or undue wear in contrast to an apparatus in which the moving part has a limit of movement, the result of the use of stops, whether such stops be protected by bluffers and dashpots or not. Moreover, when a so-called sea anchor is 115 used as a drag, it must be made heavy and cumbersome to do its work. The vanes described above are not heavy and are both located on the same side of the shaft so that both act to turn the shaft in the same direction. Moreover the mechanism operated by 120 the shaft is one which is capable of being inclosed in a watertight case which may be filled with a lubricant so that the parts are 125 kept from the corrosive action of water and are always in good operating condition. 125

This invention is not limited to the precise construction shown as it may be otherwise embodied in its various details. Moreover certain of its details may be used in connection with other buoys. The mechanism is shown in connection with a bell but other forms of signaling mechanism may be substituted therefor.

The location of a plurality of vanes projecting from the same side of a shaft is also new in a mechanism of this general class.

What I claim as my invention is:

1. In a signaling mechanism adapted to be operated by wave motion, in combination, a floating support, a signaling mechanism, a horizontal shaft capable of rotation in either direction and means for mounting it below said floating support, one or more vanes mounted on one side of said shaft and capable of movement by wave motion imparted to said floating support, connections between said shaft and said signaling mechanism whereby upon the rise and fall of the floating support signals will be given.

2. In a signaling mechanism adapted to be operated by wave motion, in combination, a floating support, a signaling mechanism, a horizontal shaft, means for mounting it on said floating support, vanes rigidly attached to said shaft to lie normally in a substantially horizontal plane whereby said shaft will be oscillated as said support rises and falls with the waves, and means connecting said shaft and said signaling mechanism whereby said shaft will cause the operation of said signaling mechanism.

3. In combination, a floating support, a horizontal rotatable shaft supported thereby, one or more vanes attached to said shaft, weights also attached to said shaft whereby said vanes will be maintained normally in a horizontal position, and signaling means and connections between said shaft and said signaling means whereby said signaling means will be operated upon the rise and fall of said floating support.

4. In combination with a buoy, a wave actuated mechanism comprising a horizontal shaft suspended below said buoy, one or more vanes projecting from one side of said shaft whereby said shaft will be turned by the rising and falling of said buoy, a signaling means connected to said shaft and adapted to be operated thereby as said shaft is turned in either direction.

5. In combination with a buoy, a horizontal shaft, vanes mounted on said shaft, means adapted to maintain said vanes normally in a horizontal plane, said vanes being adapted to rotate said shaft upon the rising and falling of the buoy, and mechanism connected to said shaft whereby signals will be given.

6. A signaling buoy comprising a float, a liquid tight casing suspended therefrom, a

signaling means, mechanism located within said casing connected to said signaling mechanism to operate it, and mechanism located outside said casing connected to the mechanism within said casing and operable by the rise and fall of said float to cause the operation of said signaling means.

7. In a buoy for signaling operable by wave motion, a float, a signal-operating mechanism suspended from said float, a horizontal shaft also suspended below said float and connected to said signal-operating mechanism, submerged vanes located on said shaft, and counterbalancing means adapted to maintain said vanes normally in a horizontal plane, whereby said vanes will act as a drag in the dead water as the float rises and falls and the shaft will be turned to operate said signal-operating mechanism.

8. In a buoy for signaling operable by wave motion, a float, a signal-operating mechanism comprising a spring, a crank pin connected to said spring to compress and release it, supporting means for said crank pin adapted to be turned by the reaction of the spring and means connected to said float whereby said crank pin will be given a continuous movement in a circular path by the rising and falling of the float.

9. In a buoy for submarine signaling, operable by wave motion, a float, a signaling mechanism and means for operating it, comprising a spring, means against which it may be compressed, a crank pin connected to said spring means to compress and release said spring, means connected to said float and said crank pin whereby said crank pin will be operated by the rise and fall of the float, and means connecting said crank pin and said signaling mechanism whereby upon the release of said spring said crank pin may have a movement independent of the movement of said spring.

10. A submarine signaling device comprising a float, a casing suspended therefrom, a bell suspended from said casing and having a clapper, a shaft supporting said clapper, mechanism partially located within said casing comprising a horizontal shaft the ends of which extend outside said casing, vanes located on said ends, connections between said clapper shaft and said vane-carrying shaft located within said casing, whereby the movement of said vane-carrying shaft will cause movements of said clapper, bearings for said shafts, and means adapted to pack the bearings of said shafts in said casing, whereby the flow of liquid therethrough will be prevented.

11. In a buoy for submarine signaling, a float, a bell and bell clapper-operating mechanism suspended below said float, a horizontal shaft connected to said bell clapper-operating mechanism, submerged vanes located on said shaft to move it, and counterbalanc-

ing means adapted to maintain said vanes normally in a horizontal plane, whereby said vanes will act as a drag in the dead water as the float rises and falls and the 5 shaft will be operated to operate said bell clapper mechanism.

12. In a buoy for submarine signaling, a float, a bell and bell clapper-operating mechanism suspended below said float, a horizontal shaft also suspended below said float and connected to said bell clapper-operating mechanism and vanes mounted on said shaft and provided with a counterbalance whereby they will normally lie in horizontal position and act as a drag in the dead water as the float rises and falls and will turn the 10 shaft to operate the bell clapper mechanism.

13. A submarine signaling buoy comprising a float, a bell and bell clapper-operating mechanism suspended from said float, a horizontal shaft, means for connecting said shaft to said bell clapper-operating mechanism whereby said shaft is rendered capable of a complete revolution, submerged vanes 20 located on said shaft, and means adapted to maintain said vanes normally in a horizontal plane, said vanes being adapted to act as a drag as the float rises and falls whereby said shaft will be operated to operate said bell 25 clapper mechanism.

14. A submarine signaling buoy comprising a float, a bell and bell clapper-operating mechanism suspended from said float, a horizontal shaft, means for connecting said shaft to said bell clapper-operating mechanism whereby said shaft is rendered capable of a complete revolution, submerged vanes 30 mounted on said shaft to have a free revolution therewith, and means adapted to maintain said vanes normally in a horizontal plane, said vanes acting as a drag as the float rises and falls, to turn said shaft.

15. In a buoy for submarine signaling, a float, a liquid-tight casing, and a bell and bell clapper suspended therefrom, a shaft 40 passing through said casing, mechanism located in said casing adapted to be operated by said shaft and to operate the bell clapper, bearings for said shaft projecting from said casing, stuffing boxes located to close the ends of said bearings, and vanes mounted on said shaft and adapted to oscillate it as the float rises and falls.

16. In combination, a floating support, a horizontal rotatable shaft supported therefrom, one or more vanes mounted thereon to turn said shaft operable by the rise and fall of the floating support, a sound producer and means connecting said shaft and 50 said sound producer comprising a spring, a rod controlled by said spring and positive means for compressing and releasing said spring comprising a crank pin and means for supporting it whereby upon the release 55 of said spring, said spring-compressing

means will be advanced, and connections between said crank pin support and said shaft.

17. In a buoy for submarine signaling, a float, a bell and a bell clapper, a crank pin, rotary supports therefor and means connecting said crank pin and said clapper whereby said clapper will be operated by the movements of said crank pin and means for operating said crank pin supports comprising a shaft, pawl plates connected thereto to 70 be rotated thereby, and carrying pawls, said crank pin supports comprising ratchets adapted to be engaged by said pawls and rotated thereby, and means for rotating said shaft.

18. In a buoy for submarine signaling, a float, a bell and a bell clapper, a crank pin, rotary supports therefor and means connecting said crank pin and said clapper whereby said clapper will be operated by the movements of said crank pin and means for operating said crank pin supports comprising a shaft carrying gears, pawl plates connected to said gears to be rotated thereby, and carrying pawls, said crank pin supports 80 comprising ratchets adapted to be engaged by said pawls and rotated thereby, and means for rotating said shaft comprising vanes mounted on said shaft on one side thereof and counterweights mounted on the 85 other side of said shaft to hold said vanes normally in horizontal position.

19. A buoy for submarine signaling comprising a casing, a clapper-operating mechanism located therein, a bell suspended from 100 said casing, said bell having a central opening in its upper portion, a clapper arm connected to said clapper-operating mechanism and passing down through said central opening, said bell having a flange projecting outwardly around said central opening and said casing having holders provided with lips 105 engaging the under side of said flange whereby the bell may be turned on said flange as a guideway.

20. A buoy for submarine signaling comprising a casing, a clapper-operating mechanism located therein, a bell suspended from said casing, said bell having a central opening in its upper portion, a clapper arm 115 connected to said clapper-operating mechanism and passing down through said central opening, said bell having a flange projecting outwardly around said central opening and said casing having holders provided with 120 lips engaging the under side of said flange whereby the bell may be turned on said flange as a guideway, said holders, their lips and the lower surface of said casing being provided with an elastic cushion to engage 125 and support said bell whereby said bell may have a slight rocking motion when struck by said clapper.

21. In a submerged signaling apparatus, a liquid tight casing and a bell and clapper 130

suspended therefrom, the lower end of said casing having a recess for the end of said clapper, bearings for said clapper forming the sides and top of said recess, a shaft passing through said recess and forming a support for said clapper and operating mechanism located in said casing and connected to said shaft.

22. In a submerged signaling apparatus, 10 an operating mechanism in a casing, a bell and clapper suspended therefrom, the lower end of said casing having a recess adapted to receive an end of said clapper and furnish bearings for the fulcrum of said clapper.

23. In a submerged signaling apparatus, a liquid tight casing, an operating mechanism located therein, a bell and clapper suspended therefrom, the lower end of said casing having a recess adapted to receive an end of said clapper and furnish bearings for the fulcrum of said clapper, and means for excluding liquid outside of said casing from said bearings.

24. In a signaling buoy, a float, a drag mechanism suspended beneath said float in substantially dead water and comprising a horizontal shaft free to rotate in either direction, a sounder, devices for operating said sounder, and means connecting said sounder-operating devices with said shaft whereby the movement of the shaft in either direction will actuate said devices.

25. In a signaling buoy, a float, a sounder 35 suspended therefrom and submerged means for operating said sounder comprising a horizontal counterbalanced shaft suspended below said float and carried thereby, a mechanism mounted on said shaft and adapted to 40 act as a drag in the dead water and cause the turning of said shaft as the float rises and falls, and mechanism connecting said shaft and said sounder whereby as said shaft turns said sounder will be operated.

26. In a signaling apparatus, a floating support, a horizontal actuating counterbalanced shaft supported below said floating support and carrying vanes whereby said shaft will be turned in either direction by 50 the rising and falling of said support, in combination with a sounder, and means connecting said shaft and said sounder comprising two ratchet and pawl mechanisms, both operable in the same direction irrespective 55 of the direction of rotation of said shaft,

and means adapted to be operated by said ratchet and pawl mechanisms in turn whereby said sounder will be operated to give out signals of uniform strength.

27. In a signaling apparatus, a float, a sounder supported therefrom and means for operating said sounder comprising a horizontal shaft carried by said float, mechanism mounted on said shaft whereby said shaft will be rotated by the rising and falling of 65 said float, and mechanism connecting said shaft with said sounder comprising a crank pin and means for giving it a rotary movement, a socket connected to said crank pin, a rod one end of which is connected to said sounder, the other end movably mounted in said socket, a spring and means connecting said spring and said rod whereby the movement of said socket in one direction will cause a corresponding movement of said rod 75 and the compression of said spring, and the release of said spring will cause a reverse movement of said rod, and the operation of said sounder.

28. In a signaling apparatus, in combination, a float, a sounder supported therefrom, a horizontal shaft also suspended from said float and means operable by the rising and falling of the float whereby the shaft will be rotated, and submerged means connected to 80 said shaft for actuating said sounder comprising a gearing system, a crank pin carried thereby and rotatable therewith, a rod connected with said crank pin, a spring and means operated by said rod whereby said 85 spring is compressed and released as the crank pin revolves.

29. In a signaling device, in combination, a float, a sounder supported therefrom, a horizontal shaft suspended from said float 95 and means located in the dead water operable by the rising and falling of the float whereby said shaft will be rotated, and means for actuating said sounder operable by said shaft, comprising ratchets, a crank 100 pin carried thereby and rotatable therewith, a rod connected with said crank pin, a spring and means connecting said spring with said rod whereby said spring will be compressed and released by said rod as the 105 crank pin revolves.

ROBERT L. WILLIAMS.
